SWITCH FOR CONTROL OF LOW VOLTAGE CIRCUITS

Alvin W. Krieger, Milwaukee, Wis., assignor to Cutler-Hammer, Inc., Milwaukee, Wis., a corporation of Delaware

Application March 18, 1937, Serial No. 131,733

19 Claims. (Cl. 201—56)

This invention relates to improvements in switches for control of low voltage circuits. Although not limited thereto, the invention is particularly applicable to multiple-position switches with light indication for speed control of motor driven automobile appliances.

An object of the invention is to generally improve the details of construction, the operation, and the appearance of switches of the aforementioned character.

Another object is to provide a novel arrangement of parts for effecting illumination of the indicating elements of the device under given conditions.

Another object is to provide novel forms of mounting means for use with a switching device of the aforementioned character.

Another and more specific object is to provide a novel form of combined switch, rheostat and indicating light affording proper speed control of low voltage driving motors.

Another object is to provide an improved form and arrangement of the wiring terminal elements of such a device.

Another object is to provide novel means for supporting and ventilating the resistance element of the device.

Other objects and advantages of the invention will be apparent or will be pointed out in the course of the following description.

The accompanying drawings illustrate certain embodiments of the invention which will now be described,—it being understood that the embodiments illustrated are susceptible of modification in respect of certain details of construction thereof without departing from the spirit and scope of the invention as defined in the appended claims.

In the drawings,

40 Figures 1 and 2 are slightly enlarged front elevational and top plan views of a multiple-speed control switch and indicating light device as constructed in accordance with my invention,—certain of the supporting elements of the device being omitted from these figures.

Fig. 3 is an enlarged top plan view, similar to Fig. 2, but with the insulating cover member and the metal member removed for purposes of illustration.

45 Fig. 4 is a vertical sectional view, on the line 4—4 of Fig. 3.

Fig. 5 is a vertical sectional view, on the line 5—5 of Fig. 3.

Fig. 6 is a side elevational view of the device 55 showing one manner of attaching the same for

support by the flange of an automobile dashboard or the like, which is shown in section.

Fig. 7 is a vertical sectional view, on the line 7—7 of Fig. 3,—the electric lamp being omitted for clarity of illustration.

Fig. 8 is a bottom plan view of the insulating base, with certain parts shown in position and other parts shown in perspective and separated relation.

Fig. 9 is a top plan view of the insulating base 10 only,—showing the formation thereof to accommodate the parts as shown in Fig. 3.

Fig. 10 is a vertical sectional view illustrating an insulating cover member, and a modified form 15 of metal member and associated parts to provide for attachment of the device to a dashboard flange.

Fig. 11 is a similar view of a further modified form of clamping support.

Fig. 12 is a sectional view of a device which may 20 be like that shown in Figs. 1 to 9, except that the screws or bolts for connecting the base, the insulating cover member and the metal member are of modified form to provide for clamping of the complete device to a dashboard flange as by 25 means of the wing nuts shown.

Fig. 13 is a perspective view, in separated relation, of certain parts of a further modified form 30 of clamping support, and

Fig. 14 is a fragmentary vertical sectional view 35 of a device having parts like those shown in Fig. 13, when clamped in position upon a dashboard flange.

Referring first to Figs. 1 to 9, inclusive, the numeral 20 designates a base molded from a suitable insulating material, such as the phenol-formaldehyde condensation product sold under the trade name of "bakelite." Base 20 is provided with a recess opening to the upper surface thereof,—said recess extending throughout the 40 major portion of the area of said base, and the same being provided with portions of different depths, as best illustrated at 21, 22 and 23 in Figs. 4, 5 and 9. The bottom wall of recess portion 21 is provided with downwardly offset ledge portions 45 24 and 25 (Figs. 5 and 9) which are adapted to accommodate the inner end portion 26 of a terminal member. Said terminal member has a vertical portion 27 and a horizontal portion 28 which extends beyond the rear end of base 20, 50 in the plane of the bottom wall of recess portion 23 (Fig. 5),—to provide for access to the wiring terminal screw 29 from above when the parts are in assembled position, as best illustrated in Fig. 2. The bottom wall of recess portion 23 is 55

preferably provided with a pair of relatively large openings 30 and 31 to afford proper ventilation or cooling of the resistance wire helix 32 which is inserted into the recess 33 which opens to the lower surface of base 20 (see Fig. 8).

Adapted to overlie the inner end portion 26 of said terminal member is a member 34 formed of resilient metal, such as phosphor bronze, which is secured to portion 26 as by means of an eyelet 35, the inner end or flange of which is accommodated within a sub-recess 36 (Fig. 5). Member 34 is provided with an integral upward extension 37 which is formed to facilitate insertion between the same and portion 27 of said terminal member of the screw shell contact 38 of an electric lamp, the bulb of which is shown at 39 (Fig. 3). Member 34 is secured to the bottom wall of recess portion 21, as by upsetting thereover the hollow shank of a rivet, as best illustrated at 40 in Figs. 4 and 7. Said rivet is provided with a shoulder 41 which is clamped, by the upsetting operation, against the lower surface of base 20. Said rivet is provided with a shoulder 42 against which the downwardly bowed intermediate portion of a contactor 43 is adapted to bear (Figs. 4 and 7); and said rivet is further provided with a shoulder or head portion 44 which is adapted to underlie and retain in pivotal relation to the lower surface of base 20 the lever 45 which is employed to actuate the contactor 43.

Lever 45 is preferably molded to the form shown from insulating material like that employed in forming base 20. As best illustrated in Figs. 4 and 8, lever 45 is provided with a recess 46 which accommodates the contactor 43 which is bowed downwardly (Fig. 4) whereby the intermediate portion thereof engages shoulder 42 and the convex end portions 47 and 48 thereof are biased upwardly toward or against the lower surface of base 20. The inner surface of lever 45 is further provided with a depression or recess 49 of arcuate form, and within the contour of recess 49 are four relatively small equally spaced recesses 50, 51, 52 and 53.

The bottom wall of the recess portion 21 (Fig. 7) is provided with a circular opening 54 with which the recesses 50 to 53 are respectively adapted to align in different rotary positions of lever 45. Located within opening 54, and having a diameter greater than the depth of said opening, is a metal ball 55. One end of metal member 34 is adapted to overlie said opening 54, and said end is preferably provided with a boss 56 to engage ball 55 and bias the same toward lever 45. Upon rotary or pivotal movement of lever 45 from each of its four predetermined positions to another thereof the ball 55 is forced upwardly in opening 54 against the bias of the aforementioned end 56 of member 34, and upon alinement of the next succeeding recess in lever 45 with opening 54 the ball 55 snaps into engagement with the circular wall of such recess to releasably retain the lever in the position to which it has thus been moved.

Lever 45 is provided at the forward end thereof with an integral extension 57 which is arranged to overlap the arcuate portion 58 of the forward end wall of base 20. Said arcuate portion 58 preferably has formed upon the vertical surface thereof four grooves 59, 60, 61 and 62 which are spaced equal angular distances with respect to each other and with respect to the center of rotation of lever 45. Said grooves represent points of rotary adjustment in which lever 45 may be positively positioned through the medium

of the ball 55 aforescribed. Extension 57 of lever 45 preferably has formed thereon (in raised outline) an arrow 63 for cooperation with the aforementioned grooves to indicate when lever 45, and the contactor 43 actuated thereby, is in one of the four positions predetermined therefor.

The upper surface of arcuate portion 58 is also preferably provided with the legends "Off", "Hi" and "Lo" positioned adjacent to the grooves 59, 60 and 62, respectively,—it being obvious that with the lever 45 in the rotary position thereof illustrated in Fig. 3 "intermediate" speed of the motor controlled by the device will be provided. In practice the aforementioned legends, as well as the arrow between the legends "Hi" and "Lo" are depressed with respect to the surface of arcuate portion 58, and thereafter such depressions are filled with paint or enamel of a color contrasting with the color of the insulating material of which base 20 is formed,—thereby increasing the visibility or legibility of the indicia.

The other wiring terminal of the device comprises an inner end portion 64 (Fig. 3) which is seated upon the bottom wall of the aforementioned recess portion 22, and is secured thereto as by upsetting thereover the hollow end of a rivet, as indicated at 65. The head 65a of said rivet is positioned upon a ledge 66 offset inwardly from the lower surface of base 20,—a resilient metal member 67 having one end thereof clamped in position by said rivet head 65a, the other end of said metal member engaging at least one coil of the resistance wire helix 32 to assist in retaining the latter in position within recess 33 and to provide an electrical connection between one end portion of said helix and the terminal 64. Terminal 64 is provided with a vertical portion 68 and a horizontal portion 69 which extends beyond the rear end of base 20, to accommodate, in an accessible position, the binding screw 70.

The rivet head 65a likewise serves as a stationary contact to be engaged by the end 48 of contactor 43 in one rotary position of lever 45. The hollow ends of rivets 71 and 72 are upset over the bottom wall of recess portion 22 (Fig. 3) and the heads 71a, 72a thereof serve as additional stationary contacts to be sequentially engaged by end portion 48 of contactor 43. One end of a resilient metal member 73 is clamped in position by rivet head 71a,—the other end of said member overlying and engaging at least one coil of helix 32 to further assist in retaining the latter in position and to provide an electrical connection between an intermediate or mid-point of the latter and the rivet head 71a. In like manner the rivet head 72a clampingly engages one end of a resilient metal member 74, the other end of the latter engaging at least one coil at the opposite end of helix 32 to assist in retaining the latter within recess 33, and to provide an electrical connection between the same and said rivet head.

Upon movement of lever 45 to the left-hand extreme position (Fig. 3) wherein the arrow 63 is alined with groove 59, the end 48 of contactor 43 is engaged with a ledge 75 which is offset inwardly from the lower surface of base 20. This is the "off" position of the switch mechanism. Upon movement of lever 45 toward the right (Fig. 3) to bring arrow 63 into alinement with groove 60 the end 48 of contactor 43 will be engaged with rivet head 65a. This provides for high speed operation of the controlled fan driving motor or the like. Thus it may be assumed

that one terminal of the battery or other source of low voltage current supply (not shown) is connected to ground,—the other terminal of such battery being connected to terminal 69, as by 5 means of binding screw 70. The circuit then extends from the portion 64 of said terminal through rivet 65 and the head 65^a thereof (see Fig. 8) to the end 48 of contactor 43 through one arm of the latter to shoulder 42 of the pivot 10 post for lever 45, through the shank of said pivot post to metal member 34 (Fig. 4), and from the latter to and through the inner end portion 26 (Fig. 5) of the other terminal member,—one terminal of the controlled motor being connected 15 to the other end 28 of the last mentioned terminal member, as by means of binding screw 29,—it being understood that the other terminal of the motor will be connected to ground.

It will be understood that under the conditions 20 just described none of the resistance of the helix 32 is included in the controlled circuit. However, upon movement of lever 45 toward the right to the position thereof shown in Fig. 3 the end 48 of the contactor will be engaged with rivet head 25 71^a (Fig. 8) to effect inclusion in the controlled circuit of that portion of the resistance of helix 32 which is located between the metal members 73 and 67. In like manner upon movement of lever 45 to its extreme right-hand position (Fig. 30 3) the end 48 of the contactor will be engaged with rivet head 72^a (Fig. 8) with consequent inclusion in the controlled motor circuit of all of the resistance of helix 32 which is located between the metal members 74 and 67,—for low 35 speed operation of the fan driving motor. The front end wall of base 20 (Fig. 3) is preferably provided with vertical ribs or projections 75 and 76 for engagement by the projecting portion or handle 57 of lever 45 to positively limit the degrees of rotation of said lever in opposite directions. It is to be understood that in all positions of contactor 43 the end 47 thereof (Figs. 4 and 8) will be engaged with the flat lower surface of base 20 to assist in tensioning said contactor.

The arrangement is also such that a circuit is completed for effecting illumination of lamp 39 when lever 45 is in either of its high speed, intermediate speed, or low speed positions. This 50 result is obtained by providing means for grounding the center lamp socket contact 77,—the screw shell socket contact 37 being electrically connected with the wiring terminal 28 which is connected with the controlled motor, as aforescribed. Inasmuch as I prefer to provide a molded insulating cover member 78 for base 20, I effect grounding of center lamp socket contact 77 by electrically and mechanically connecting the same with the metal member 79 (Fig. 7) as 55 by welding, brazing or soldering the flat end portion 80 of the former to the latter. Insulating cover member 78 is provided with an opening 31 to provide for insertion of contact 77 therethrough into the portion 21 of the base recess. 60 Base 20 is provided in its upper surface (Fig. 3) with tapped recesses 81 and 82, and insulating cover member 78 and metal member 79 are provided with openings registering with said recesses, to provide for threading of the screws or bolts 83 and 84 (Fig. 2) into said recesses, whereby the base 20, cover member 78 and metal member 79 are retained in assembled relation. Cover member 78 is provided at its rear end with a 65 downwardly projecting rib 85,—the opposite ends 70 of which respectively fit into notches 86 and 87

provided in the side walls of base 20. The front end wall of base 20 does not extend to the upper surface of the latter, as indicated at 88 in Figs. 3 to 6; whereas the cover member 78 is formed, as shown at 89 in Figs. 4 to 6, to overlap the forward end of base 20. The forward end of cover member 78 is formed to provide a hood or cowl 90,—the recess 91 in the latter (Figs. 4 and 5) providing for indirect lighting of the exterior surface of the forward end wall of base 20; and 10 particularly the portion 58 thereof containing the indicating legends aforementioned.

The parts are arranged and formed as best illustrated in Fig. 1 to provide a neat and attractive appearance of the surfaces which are exposed when the complete device is mounted to a dashboard flange. One manner of mounting the device is illustrated in Fig. 6. Thus as shown in Figs. 4 to 6, the upper surface of cover member 78 is provided with a recess 92 which is adapted 15 to accommodate one arm 93 of a substantially U-shaped metal clamping bracket 94, the other arm 95 of which is provided with a tapped opening to receive the threaded shank of a manually adjustable bolt 96.

The metal dashboard of an automobile is shown at 97 in Fig. 6,—the same having a horizontal flange 98 the upper surface of which is engaged by the lower end of bolt 96, whereby the metal member 79 is clamped against the lower surface of said flange. Member 79 may, if desired, have the four corners thereof bent upwardly to provide teeth 99 which bite into the lower surface of flange 98 to afford a good mechanical and electrical connection between these parts.

As shown in Figs. 3 to 5 and 8 the recess 33 in the lower surface of base 20 may have positioned therein a member 100 of inverted channel-shape formed of a suitable heat-resisting insulating material. The upper end portion of member 100 is provided with openings 101 and 102 (Figs. 3 and 5) of a size substantially corresponding to the aforementioned openings 30 and 31 in the bottom wall of recess portion 23 to minimize the obstruction to upward flow of cooling air through the coils of helix 32 when the latter is in heated condition.

As best illustrated in Figs. 4, 5 and 8 the ledge 66 is provided with a pair of bosses 103 and 104 to assist in restraining the metal members 67 and 74 against rotary displacement,—member 73 (Fig. 8) being similarly restrained by positioning of the free end thereof within the recess 105. The rear end of base 20 is preferably provided with a rib 106 to properly insulate the terminal members, 28 and 69, and binding screws 29 and 70, from each other, said rib preferably extending a substantial distance above the upper surface of base 20 for properly insulating said terminals from bracket arm 93 during attachment of the device to flange 98. Member 79 may be provided with ribs 107 and 108, if desired.

After wiring of the device, the same may be readily and quickly positioned and secured at the desired point upon the dashboard flange, in the manner shown in Fig. 6. As will be apparent from the foregoing description, a device so constructed and mounted provides for exposure or visibility of only parts which are formed of insulating material, such parts being so formed as to provide a pleasing and attractive appearance of the device.

In the modified form of supporting means shown in Fig. 10 the insulating cover member 78

has superimposed thereupon a metal member 109 which is substantially like the metal member 79 aforescribed. However, member 109 is formed to provide a downwardly opening recess 110 of 5 rectangular contour to receive and prevent rotation of the correspondingly shaped head 111 of a bolt the threaded shank 112 of which is freely insertable upwardly through openings in member 109 and flange 98 for cooperation with 10 a clamping nut 113 of suitable form,—a split lock washer 114 being preferably interposed between flange 98 and said nut to restrain the latter from loosening. Also attached to member 109, as by upsetting the reduced end portion 115 15 thereof over the lower surface of said member, is a stud 116 which extends upwardly into an opening provided in flange 98 to positively restrain member 109 against rotary displacement relatively to flange 98. The other elements of 20 the device illustrated in Fig. 10 may be identical with the corresponding parts aforescribed.

In the device of Fig. 11 the plate 79^a may have attached thereto a stud 116, such as shown in Fig. 10, for cooperation with the walls of an opening in flange 98. A screw or bolt 117 of ordinary form may have the threaded shank thereof threaded into an opening in member 79^a and extending upwardly through an opening in flange 98 to receive the clamping nut 113. Lock washers 30 114 are respectively interposed between the bolt head 117 and member 79^a and between nut 113 and flange 98 to prevent accidental turning or loosening of these parts.

In the device of Fig. 12 I substitute for the bolts or screws 83 and 84 of Fig. 2 a pair of specially formed bolts the shanks 118 and 119 of which take into the tapped openings 81 and 82 in base 20,—said bolts having flanges 118^a and 119^a which engage metal member 79^a to retain the latter and base 20 and cover member 78 in assembled relation. Said bolts are provided with enlarged threaded upper ends 118^b and 119^b which penetrate corresponding openings in flange 98,—a pair of wing nuts 118^c and 119^c being adapted for cooperation with said upper ends to clamp the device to said flange. Said upper ends of the bolts may be provided with kerfs 118^d and 119^d to facilitate insertion of the shanks 118 and 119 into said base recesses.

50 In the modification shown in Figs. 13 and 14 the insulating cover member 120 is specially provided with a recess 121 in the upper surface thereof of a shape and size to receive with a fairly snug fit the square head 122 of a bolt the threaded shank 123 of which extends upwardly through an opening in metal member 79^a and in flange 98 for cooperation with a clamping nut 113 of usual form,—a lock washer 114 being preferably interposed between said nut and the flange 98. Member 79^a has attached thereto a stud 116 (like that shown in Fig. 11) to cooperate with an opening in flange 98 whereby rotary displacement of metal member 79^a with respect to the flange 98 is prevented. With such an arrangement there is no necessity for bending up the corners of metal member 79^a to provide the teeth shown at 99 in Figs. 1 and 2.

Although the base 20 and cover member 78 are ordinarily molded from insulating material of like 70 character and color, it may in some instances be desirable to make these parts of contrasting colors. Similarly, the insulating material of the base 20 and cover member 78 may be opaque to light generated in lamp 39, or the material of 75 which one or both of these parts is made may be

more or less translucent. Where a translucent material is employed in the manner just described the lighting effect provided by the passage afforded by recess 91 may not be necessary.

What I claim as new and desire to secure by 5 Letters Patent is:

1. In combination, a molded insulating base having a recess formed in the upper surface thereof, a pair of wiring terminal members having portions thereof located within said recess and rigidly secured to the bottom wall of the latter, a resilient contact rigidly attached to one of said terminal members within said recess, said contact being formed to yieldably receive and retain the screw shell contact of an electric lamp, a molded insulating member adapted to cover a portion of said recess and having an opening formed therein, a metal member superimposed upon said insulating member, said metal member having a resilient contact attached thereto which penetrates said opening for yieldable engagement with the center contact of said electric lamp, common means for rigidly but releasably attaching said metal member and said insulating member to said base, a plurality of stationary contacts rigidly attached to the bottom surface of said base, a molded insulating actuating member pivotally supported upon said bottom surface of said base, a contactor carried by said actuating member for movement by the latter into and out of engagement with the respective stationary contacts, and means for continuously providing an electrical connection between said contactor and the terminal member to which said first mentioned resilient contact is attached. 35

2. In combination, a molded insulating base having a recess formed therein and opening to the upper surface thereof, a pair of wiring terminal members having portions thereof located within said recess and rigidly secured to the bottom wall of the latter, a resilient contact rigidly attached to one of said terminal members within said recess, said contact being formed to yieldably receive and retain the screw shell contact of an electric lamp, a molded insulating member adapted to cover a portion of said recess, said insulating member having an opening formed therein, a resilient contact penetrating said opening and adapted for engagement with the center contact of an electric lamp located within said recess, a metal member to which said last mentioned contact is rigidly attached to provide an electrical connection therebetween, a stationary contact rigidly attached to the bottom surface of said base and electrically and mechanically connected with the other terminal member, two additional stationary contacts secured to the bottom surface of said base, said contacts being arranged in arcuately spaced relation, a recess formed in the bottom surface of said base, a helix formed of resistance wire and located within said last mentioned recess, resilient metal members associated with the respective stationary contacts and adapted to underlie and engage said helix at spaced points on the latter, an insulating actuating member pivotally supported upon said base at the lower surface of the latter, and a contactor carried by said actuator and movable by the latter from an extreme off position into engagement with said stationary contacts in sequence, said contactor being continuously electrically connected with the terminal member to which said first mentioned resilient contact is attached. 50

3. In combination, a molded insulating base having a recess formed therein and opening to 75

the upper surface thereof, a pair of wiring terminal members having portions thereof located within said recess and rigidly secured to the bottom wall of the latter, a resilient contact rigidly attached to one of said terminal members within said recess, said contact being formed to yieldably receive and retain the screw shell contact of an electric lamp, a molded insulating member adapted to cover a portion of said recess, said insulating member having an opening formed therein, a stationary contact rigidly attached to the bottom surface of said base and electrically and mechanically connected with the other terminal member, two additional stationary contacts secured to the bottom surface of said base, a recess formed in the bottom surface of said base, a helix formed of resistance wire and located within said last mentioned recess, resilient metal members associated with the respective stationary contacts and adapted to underlie and engage said helix at spaced points on the latter, an insulating actuating member pivotally supported upon said base at the lower surface of the latter, a contactor carried by said actuator and movable by the latter from an extreme off position into engagement with said stationary contacts in sequence, one of said terminal members being adapted for connection with a suitable source of low voltage current supply, the other terminal member being adapted for connection to ground through an electrical translating device of suitable form, and clamping means associated with said metal member to provide for electrical connection of the latter to ground and to provide suitable supporting means for the switch.

4. In combination, a molded insulating base having a recess formed in the upper surface thereof, a pair of resilient contacts located within said recess and adapted for cooperative engagement with the center and screw shell contacts of an electric lamp, means including a metal supporting member for said base to provide for electrical connection of one of said contacts to ground, means including a wiring terminal member having a portion thereof located within said recess to which the other of said contacts is electrically connected, a contactor positioned upon the lower surface of said base and continuously electrically connected with said terminal member, a molded insulating actuating member pivotally supported at said lower surface of the base, said contactor being interlocked with said actuating member to provide for rotation of the former by the latter, said actuating member having a plurality of arcuately arranged recesses formed therein and said base having a spring biased member for cooperation with the walls of said recesses to yieldably retain said actuating member and said contactor in any one of a number of different positions, said contactor in one extreme position being adapted to interrupt the circuit to be controlled thereby, said base having a plurality of stationary contacts upon said lower surface of the base into engagement with which said contactor may be moved in sequence, the contact first engaged by said contactor upon movement of the latter from said extreme position having a wiring terminal to provide for direct connection thereof to a suitable low voltage current source, and a resistance wire helix, said base having a recess formed in the lower surface thereof to accommodate said helix, said contacts being respectively electrically connected with said

helix at spaced points on the latter, whereby upon continued movement of said contactor into engagement with the other contacts sequentially predetermined values of said resistance are included in the controlled circuit.

5. In combination, a base having an upwardly opening recess, a cover member therefor, and an actuating lever each formed of molded insulating material, a wiring terminal member having a portion thereof located within said recess, a resilient metal member rigidly attached to said portion of the terminal member and having a contact portion adapted for cooperation with the screw shell contact of an electric lamp, a headed rivet the shank of which extends upwardly through said actuating lever, said base and said metal member and is upset over the latter to provide for pivotal support of said lever, said lever having a recess formed in the upper surface thereof, a contactor positioned within said last mentioned recess and having end portions biased outwardly from the latter, the shank of said rivet having a shoulder engaged by the intermediate portion of said contactor to provide a continuous electrical connection between the latter and said terminal member, the bottom wall of said base recess having an opening formed therein, a ball located within said opening, said resilient metal member having a portion thereof overlying said opening and engaging said ball to bias the same against said actuating lever, said lever having a plurality of arcuately arranged relatively shallow recesses formed therein to accommodate said ball and to thereby indicate to the touch the respective on and off positions of said contactor, said base having a plurality of stationary contacts upon the lower surface thereof, said contactor being movable by said lever to disengage all of said stationary contacts or to engage the same in sequence, and a second wiring terminal member electrically connected with one of said stationary contacts to provide for substantially direct connection of said contactor with a suitable source of current supply.

6. In combination, a molded insulating base having an upwardly opening recess formed therein, center and screw shell lamp socket contacts positioned within said recess for cooperation with the center and screw shell contacts of an electric lamp, a molded insulating cover member superimposed upon said base, said cover member being formed to provide for indirect illumination by said electric lamp of the exterior surface of the forward end wall of said base, a pair of wiring terminal members having portions thereof attached to said base within said recess and having wire attaching portions thereof exposed exteriorly of said base, one of said lamp socket contacts being electrically connected with one of said terminal members, a stationary contact positioned upon the lower surface of said base and electrically connected with the other terminal member, a contactor positioned upon the lower surface of said base and electrically connected with said first mentioned terminal member, an insulating actuating member pivotally supported upon the lower surface of said base and having an interlocking connection with said contactor to provide for movement of the latter into and out of engagement with said stationary contact upon pivotal movement of said actuating member, and said actuating member having an integral portion thereof adapted for cooperation with the forward end wall of said

base to visually indicate the respective on or off positions of the switch.

7. In combination, a molded insulating base having an upwardly opening recess formed therein, center and screw shell lamp socket contacts positioned within said recess for cooperation with the center and screw shell contacts of an electric lamp, a molded insulating cover member superimposed upon said base, said cover member being 5 formed to provide for indirect illumination by said electric lamp of the exterior surface of the forward end wall of said base, a pair of wiring terminal members having portions thereof within said recess and having wire attaching portions 10 thereof exposed exteriorly of said base, said screw shell lamp socket contact being permanently electrically connected with one of said terminal members, a stationary contact positioned upon the lower surface of said base and permanently 15 electrically connected with the other terminal member, a contactor positioned upon the lower surface of said base and continuously electrically connected with said first mentioned terminal member, an insulating actuating member pivotally supported upon the lower surface of said base and adapted to effect movement of the contactor 20 into and out of engagement with said stationary contact, said actuating member having an integral portion thereof adapted for cooperation 25 with the forward end wall of said base to visually 30 indicate the respective on or off positions of the switch, a metal member superimposed upon said cover member, said metal member having an electrical connection with the aforementioned 35 center lamp socket contact to provide for grounding of the latter, associated means for rigidly connecting said metal member, said cover member and said base in assembled relation, and associated clamping means for electrically and 40 mechanically connecting said metal member to the metal flange of an automobile dashboard or the like.

8. In combination, a molded insulating base having an upwardly opening recess formed therein, center and screw shell lamp socket contacts positioned within said recess, a molded insulating cover member superimposed upon said base, a pair of wiring terminal members having portions thereof within said recess and having wire attaching portions thereof exposed exteriorly of 45 said base, said screw shell lamp socket contact being permanently electrically connected with one of said terminal members, a stationary contact positioned upon the lower surface of said base and permanently electrically connected with the other terminal member, a contactor positioned upon the lower surface of said base and continuously electrically connected with said first mentioned terminal member, an insulating 50 actuating member pivotally supported upon the lower surface of said base and having an interlocking connection with said contactor to provide for movement of the latter into and out of engagement with said stationary contact, said actuating member having an integral portion thereof adapted for cooperation with the forward end wall of said base to visually 55 indicate the respective on or off positions of the switch, a metal member superimposed upon said cover member, said metal member having an electrical connection 60 with the aforementioned center lamp socket contact to provide for grounding of the latter, associated means for rigidly connecting said metal member, said cover member and said base in assembled relation, and associated means for 65

electrically and mechanically connecting said metal member to the metal flange of an automobile dashboard or the like, said last mentioned means comprising a screw threaded bolt and an element cooperating with said bolt to clamp said 5 metal member in position.

9. In combination, a molded insulating base having an upwardly opening recess formed therein, center and screw shell lamp socket contacts positioned within said recess, a molded insulating cover member superimposed upon said base, said cover member being formed to provide for indirect illumination by said electric lamp of the exterior surface of the forward end wall of said base, a pair of wiring terminal members having portions thereof within said recess and having wire attaching portions thereof exposed exteriorly of said base, one of said lamp socket contacts being permanently electrically connected with one of said terminal members, a stationary contact 20 positioned upon the lower surface of said base and continuously electrically connected with the other terminal member, a contactor positioned upon the lower surface of said base and continuously electrically connected with said first mentioned terminal member, an insulating actuating member pivotally supported upon the lower surface of said base and having an interlocking connection with said contactor to provide for movement of the latter into and out of engagement 25 with said stationary contact, a plurality of additional stationary contacts positioned upon the lower surface of said base, said stationary contacts being arcuately arranged in spaced relationship to each other, said base having a downwardly opening recess formed therein, a resistance wire helix insertable into said last mentioned recess, said stationary contacts being respectively electrically connected with said helix at spaced points on the latter, for the purpose 30 set forth, and said actuating member having a portion thereof overlapping and cooperating with the forward end wall of said base to visually indicate the on or off position of the switch and the relative value of resistance included in the circuit controlled thereby.

10. In combination, a molded insulating base having an upwardly opening recess formed therein, center and screw shell lamp socket contacts positioned within said recess, a molded insulating cover member superimposed upon said base, said cover member being formed to provide for indirect illumination by said electric lamp of the exterior surface of the forward end wall of said base, wiring terminal members having portions thereof within said recess and having wire attaching portions thereof exposed exteriorly of said base, one of said lamp socket contacts being permanently electrically connected with one of said terminal members, a stationary contact positioned upon the lower surface of said base and continuously electrically connected with said first mentioned terminal member, an insulating actuating member pivotally supported upon the lower surface of said base and having an interlocking connection with said contactor to provide for movement of the latter into and out of engagement with said stationary contact, a plurality of additional stationary contacts positioned upon the lower surface of said base, said base having a downwardly opening recess formed therein, a resistance wire helix insertable into said last mentioned recess, the upper end wall of said last mentioned recess 70

having a plurality of relatively large openings formed therein to provide for substantially free circulation of air through said helix, said stationary contacts being respectively electrically connected with said helix at spaced points on the latter, and said actuating member having a portion thereof overlapping and cooperating with the forward end wall of said base to visually indicate the on or off position of the switch and the relative value of resistance included in the circuit controlled thereby.

11. The combination with a molded insulating base having an upwardly opening recess formed therein to accommodate an electric lamp, center and screw shell lamp socket contacts located within said recess for cooperation with the contacts of a lamp, a molded insulating cover member superimposed upon said base and adapted to overlie said recess, said cover member being formed to provide for indirect passage of light from said lamp to an exterior portion of the forward end wall of said base, a plurality of stationary contacts positioned upon the lower surface of said base, a molded insulating actuating member pivotally supported at the lower surface of said base, said actuating member being adapted to underlie said stationary contacts whereby the latter are concealed, said actuating member having a recess facing said lower surface of said base, a contactor located within said last mentioned recess and movable by said actuator into and out of engagement with the respective stationary contacts in sequence, a metal member superimposed upon said cover member in inwardly offset relation to the forward end of the latter, and clamping means associated with said metal member to provide for attachment of the device to the bottom flange of an automobile dashboard or the like, the arrangement being such that only insulating parts of the device are visible to the user under normal conditions.

12. In combination, a molded insulating base, a switch mechanism carried thereby, said mechanism including an insulating actuating lever pivotally supported by said base at the lower surface thereof for movement in a plane parallel to the latter, said lever having an integral extension overlapping a portion of the front end wall of said base and cooperating with suitable legends on the latter to indicate the relative positions of the switch parts, a molded insulating member positioned upon the upper surface of said base, said insulating member having a recess formed therein and opening to the upper surface thereof, a metal member superimposed upon the upper surface of said insulating member and adapted to overlie said recess, common means for connecting said metal member, said insulating member and said base to each other, said metal member being adapted to underlie the bottom flange of an automobile dashboard or the like, means comprising a metal attaching member having a portion thereof located within said recess and another portion thereof extending above the upper surface of said flange, a screw-threaded member positioned above said flange and cooperating with said last mentioned portion of said metal attaching member for clamping said first mentioned metal member to said flange.

13. In combination, a molded insulating base, a switch mechanism carried thereby, said mechanism including an insulating actuating lever pivotally supported by said base at the lower surface thereof for movement in a plane parallel to the latter, said lever having an integral exten-

sion overlapping a portion of the front end wall of said base and cooperating with suitable legends on the latter to indicate the relative positions of the switch parts, said front end wall and said extension being cooperatively formed to limit the movements of said lever in opposite directions respectively, a molded insulating member positioned upon the upper surface of said base, said insulating member having a recess formed therein and opening to the upper surface thereof, a metal member superimposed upon the upper surface of said insulating member and adapted to overlie said recess, common means for connecting said metal member, said insulating member and said base to each other, said metal member being adapted to underlie the bottom flange of an automobile dashboard or the like, means comprising a metal attaching member having a portion thereof located within said recess and another portion thereof extending above the upper surface of said flange, and a screw-threaded member positioned above said flange and cooperating with said last mentioned portion of said metal attaching member for clamping said first mentioned metal member to said flange.

14. In combination, a molded insulating base, a switch mechanism carried thereby, said mechanism including an insulating actuating lever pivotally supported by said base at the lower surface thereof for movement in a plane parallel to the latter, said lever having an integral extension overlapping a portion of the front end wall of said base and cooperating with suitable legends on the latter to indicate the relative positions of the switch parts, a molded insulating member positioned upon the upper surface of said base, said insulating member having a recess formed therein and opening to the upper surface thereof, a metal member superimposed upon the upper surface of said insulating member and adapted to overlie said recess, common means for connecting said metal member, said insulating member and said base to each other, said metal member being adapted to underlie the bottom flange of an automobile dashboard or the like, means comprising a metal attaching member having a portion thereof located within said recess and another portion thereof extending above the upper surface of said flange, a screw-threaded member positioned above said flange and cooperating with said last mentioned portion of said metal attaching member for clamping said first mentioned metal member to said flange, said flange having an opening formed therein and said first mentioned metal member having a stud of corresponding size projecting upwardly through said opening, whereby said first mentioned metal member is positively restrained against rotary displacement relatively to said flange.

15. In combination, a molded insulating cover member having a recess of non-circular contour formed in the upper surface thereof, a fastening member having a head of substantially corresponding contour seated within said recess and restrained by the walls of the latter against relative rotation, said fastening member having a threaded shank extending upwardly from said recess, a metal member superimposed upon said cover member and having an opening to freely accommodate said shank, a support comprising a flange which overlies said metal member, said flange also having an opening to freely accommodate said shank, and a nut cooperating with said shank and movable into clamping engage-

ment with the upper surface of said flange, whereby said metal member is clamped in position against the lower surface of said flange.

16. In combination, a molded insulating cover member having a recess of non-circular contour formed in the upper surface thereof, a fastening member having a head of substantially corresponding contour seated within said recess and restrained by the walls of the latter against relative rotation, said fastening member having a threaded shank extending upwardly from said recess, a metal member superimposed upon said cover member and having an opening to freely accommodate said shank, a support comprising a flange which overlies said metal member, said flange also having an opening to freely accommodate said shank, a nut cooperating with said shank and movable into clamping engagement with the upper surface of said flange, whereby said metal member is clamped in position against the lower surface of said flange, means interposed between the upper surface of said flange and said nut to releasably restrain the latter against rotary displacement, said metal member having a stud attached thereto and extending upwardly therefrom, and said flange having an opening of corresponding size to accommodate said stud, whereby rotary displacement of said metal member relatively to said flange is positively prevented.

17. In combination, an insulating base, a pair of wiring terminal members carried by said base, a pair of resilient lamp socket contacts, one of which is electrically connected with one of said wiring terminal members, a molded insulating member adapted to cover at least a portion of said base, a metal member superimposed upon said insulating member, common means for rigidly and releasably attaching said metal member and said insulating member to said base, a resistance element supported by said base, a plurality of stationary switch contacts on said base, means providing electrical connections between said switch contacts and said resistance element at spaced points on the latter, and a contactor movable into and out of engagement with said switch contacts selectively to effect completion and interruption of a circuit for a suitable energy translating device and to effect inclusion of said resistance in or exclusion thereof from said circuit.

18. In combination, a molded insulating base having a recess formed in the upper surface

thereof, a pair of wiring terminal members having portions thereof located within said recess and rigidly secured to the bottom wall of the latter, a resilient contact rigidly attached to one of said terminal members within said recess, said contact being formed to yieldably receive and retain the screw shell contact of an electric lamp, a molded insulating member adapted to cover a portion of said recess and having an opening formed therein, a metal member superimposed upon said insulating member, said metal member having a resilient contact attached thereto which penetrates said opening for yieldable engagement with the center contact of said electric lamp, and common means for rigidly but releasably attaching said metal member and said insulating member to said base.

19. In combination, a molded insulating base having a recess formed in the upper surface thereof, a pair of resilient contacts located within said recess and adapted for cooperative engagement with the center and screw-shell contacts of an electric lamp, means including a metal supporting member for said base to provide for electrical connection of one of said contacts to ground, means including a wiring terminal member having a portion thereof located within said recess to which the other of said contacts is electrically connected, said terminal member being adapted for connection with a translating device of suitable form, a contactor positioned upon the lower surface of said base and continuously electrically connected with said terminal member, an actuating member pivotally supported at said lower surface of the base, said contactor being interlocked with said actuating member to provide for rotation of the former by the latter, said actuating member having a plurality of arcuately arranged recesses formed therein and said base having a spring biased member for cooperation with the walls of said recesses to yieldably retain said actuating member and said contactor in any one of a number of different positions, said contactor in one extreme position being adapted to interrupt the circuit to be controlled thereby, and said base having a plurality of stationary contacts arranged in arcuate formation upon said lower surface of the base into engagement with which said contactor may be moved in sequence.

ALVIN W. KRIEGER.
